(57) **CLAIM**

The ornamental design for a flashlight, as shown and described.

DESCRIPTION

FIG. 1 is a top, right front perspective view of a flashlight in accordance with the present invention;

FIG. 2 is a top, left rear perspective view of the flashlight;

FIG. 3 is a front view of the flashlight;

FIG. 4 is a rear view of the flashlight;

FIG. 5 is a left side view of the flashlight;

FIG. 6 is a right side view of the flashlight;

FIG. 7 is a top view of the flashlight;

FIG. 8 is a bottom view of the flashlight; and,

FIG. 9 is the top, left rear perspective view of the flashlight, but including an optional connector accessory in broken line.

The broken lines shown represent portions of the article and form no part of the claimed design.

1 Claim, 7 Drawing Sheets
